OLNEY ARNOLD, OF PAWTUCKET, RHODE ISLAND.

Letters Patent No. 96,184, dated October 26, 1869.

IMPROVEMENT IN MACHINES FOR CUTTING CORK.

The Schedule referred to in these Letters Patent and making part of the same.

To all whom it may concern:

Be it known that I, OLNEY ARNOLD, of Pawtucket, in the county of Providence, and State of Rhode Island, have invented a new and improved Machine for Cutting Corks; and I do hereby declare that the following is a full, clear, and exact description of the construction and operation of the same, reference being had to the accompanying drawings, making a part of this specification, in which—

Figure 1 is a side elevation.

Figure 2 is a plan.

Figure 3 is a cross-section through the line xx of fig. 1.

Figure 4 is an outline perspective view of the cutting-instrument.

The object of the invention is to provide for public use a machine which will grasp the bark, hold it firmly, and apply the cutting-knives to it in such a manner as to cut out the corks rapidly, with great perfection, and with the utmost economy of material, each movement of the operator's lever producing a large number of finely-cut corks.

To accomplish this object, I employ a machine consisting of the following parts, to wit:

First, a supporting-frame.

Second, two reciprocating frames, which travel back and forth toward and from each other, and each of which supports a system of cutter-shafts.

Third, a large number of rotary cutter-shafts, with cutter-heads sliding longitudinally upon them.

Fourth, a compound lever-device, which, by a single movement, first advances the two reciprocating-frames till they grasp and hold the bark firmly, and then forces the cutters against it, on each side, while they are rapidly revolving.

Fifth, an adjustable table, for holding the bark.

Sixth, a system of gear-wheels, that operate the cutter-shafts, so arranged as to allow the latter to be moved back and forth in connection with the two sliding frames without being thrown out of gear.

Seventh, a cutter-head, and knives, of peculiar construction and operation.

All these parts will now be more particularly described, and their combination and mutual adaptation and operation explained, with reference to said drawings, in which—

F represents the supporting-frame;

A A', the two reciprocating-frames, which travel back and forth toward and from the cork-table T;

B B', the two systems of cutter-shafts, the former connected with the frame A, and the latter with the frame A';

C C', two transverse gear-wheel shafts, supported by and travelling with the two frames A A';

D, a longitudinal power-shaft, which drives all the cutters, it being connected to the two shafts C C', by means of bevel-gear wheels d d' , which slide upon it as the frames A A' move back and forth, and thereby always remain in gear with the cross-shafts C C';

d d' c c' , the bevel-gear, which transmit motion from shaft D to the shafts C C' and c^2 c^3 c^4 c^5 , the gear which transmit motion from shafts C C' to the cutter shafts;

t t , the adjusting-screws, which regulate the height of the table T, that supports the bark while the frames A A' are approaching it; and

T, a frame, pivoted to frame F, at t , and serving, when turned down, (as shown in fig. 1,) to press upon the upper edge of the bark, and clamp the latter between the two parts T T'.

As thus far described, it is evident that the machine is capable of holding the bark in position, and, by means of the two frames A A', bringing all the cutters against it while revolving at a high speed, and thereby cutting out the corks rapidly, a large number at a time, some of the cutters making their incision upon one side, and some upon the other side of the bark, so as not to disturb the latter, or force it from its place.

The machine, as thus far described, is, however, not perfect.

In connection with the parts referred to, I employ sliding knives, which, revolving with the cutter-shafts, receive the motion of the frames A A', and at the same time have an independent movement of their own, in a manner which I will now describe.

b b' are the cutter-heads, each being nearly in the shape of a perfect cork, and fixed at the end of its shaft, B or B'.

Through slots in each cutter-head extend the knives e e' , which are so connected by rods or links, e^2 , to a cross-beam, E E', that, by sliding the latter forward and back, the knives e e' well advance or recede on the shafts B B', so as to project from the faces of the cutter-heads, or to be entirely concealed therein.

The drawings show both positions of the knives.

It is evident that the cross-bar E E' cannot change position, to accommodate the rotation of the knives. I therefore connect the links e^2 to spool-formed disks, e^3 , which rotate with the cutter-shafts.

The cross-bar E E' is so shaped that a flange upon its upper side projects into the groove in the perimeter of the disks e^3 , on their upper side, and another, on its under side, projects into the same groove on their under side, thus leaving the disks free to rotate with the cutter-shafts, but causing them to slide back and forth, independently of said shafts, whenever the cross-pieces E E' are moved back and forth.

The sliding disks e^2 , as well as the gear-wheels d d' , are connected with their shafts by the well-known

tongue-and-groove device, by which they are compelled to rotate with their shafts, although free to change place upon them.

The form of the knives *e e* is clearly shown in fig. 4 and in fig. 2.

Each knife is a curved blade, with convex edge at the end, and a shank, link, or connecting-rod, *c'*, at its rear edge, which runs back, and is attached to the disk *c*. One, two, or more (preferably two) of the blades may be used with each cutter-head.

The object of the peculiar construction of the cutting-apparatus above described is, that when the bark is in place between the parts *T T'*, the movement of the frames *A A'* may bring the cutter-heads fairly up to it, or against it, on each side, so as by lateral pressure to hold it tightly before the knives are applied to it; and after the parts reach this position, an independent forward movement of the cross-piece *E E'* may advance the knives through the slotted cutter-heads, and, while they are rapidly revolving with their shafts, apply them to the bark simultaneously, thus cutting out with the knives a large number of corks at once, while the smooth faces of the cutter-heads hold the bark accurately and firmly in place during the operation.

In order that cutter-heads of different sizes may be employed, for the purpose of making larger or smaller corks, I make the axle-boxes or bearings *i i*, of shafts *B B'*, movable, and clamp them in a slot in the cross-beams of the frames *A A'*, by means of screws *G G* and blocks *H H*, (fig. 3,) the latter being thicker or thinner, according to the different sizes of corks required.

To cut large corks, I insert thick blocks *H H* between the boxes *i i*, and clamp the whole firmly together by the screws *G G*. To cut small corks, I use thin blocks *H H*, in place of the thick ones.

The gear-wheels *c² c'* can be confined in any required position on their shafts *C C'*, by means of a key and seat, so as to accommodate them to any position of the cutter-shafts.

In order that, when the blades *e e* become worn, they may not be retracted by the motion of the bar *E* so far as to fall out of their sockets, I provide adjustable stops *I I*, screwing through the cross-beam *A*, as shown in fig. 2, so as to arrest the backward movement of the part *E* at any desired point.

A² A³ are platforms under the cutter-shafts, constituting a part of the frames *A A'* respectively, and each of the two frames *A A'* with the cutter-shafts, and all the apparatus that moves with the frames may be covered with a box, *K*, (one of which boxes is shown in fig. 1,) so as to conceal the working parts from view and protect them from dust, &c., and at the same time enable the operator to do his work with less danger of entangling his clothes among the shafts, &c.

The boxes may have suitable doors in any convenient position, so that the workmen can get at the machinery, when necessary.

The front or adjacent edges of the two boxes should be vertical, and parallel to each other. The knives should, when advanced, project through such front edges or faces. The cutter-heads may project through, or may not come out flush with such vertical face, as the constructor shall judge best. If they project through, they will come against the bark and hold it while revolving in contact with it, but if they do not project through, the front edges of the boxes will come against the bark and hold it—and as the boxes have no rotary motion, this will be undoubtedly the best arrangement. I wish to be free, however, to employ either means of holding the bark.

The part *T'* folds down over one of the boxes, and is provided with adjustable screws, *T'*, which can be

screwed up or down, so as to rest properly upon the uneven edge of the bark.

An eccentric button, *U*, with an inclined under face, serves to force the part *T'* down, and hold its screws in contact with the bark, the button itself being supported by an elevated cross-piece, *U'*.

Having thus described the several parts of my machine, above referred to, it remains to explain the means by which, through a single vertical movement of one lever, the frames *A A'* and the cutter-blades *e e* can be first advanced or retracted together, and after that the motion of the frames be made to cease, and that of the blades continue independently of the frames. The apparatus by which this is effected is as follows:

A rock-shaft, *M M'*, under each frame, and connected thereto by two arms, *m m' m' m*, serves to move the respective frames back and forth.

Another rock-shaft, *N N'*, also under each frame, (the two shafts *N N'* lying between the two *M M'*,) and connected to the cross-beam *E* by two arms *n n' n' n'*, serves to move the cutter-blades back and forth independently of the frames *A A'*.

Crank, *O O'*, are fixed to the ends of the two shafts *M M'*, and the ends of the cranks are connected by a pin and slot, *o*, to a slide, *Q*, which works up and down between vertical guides or slide-bars *q q'*.

As the slide *Q* is moved upward, it retracts both frames *A A'* simultaneously, and when moved downward, brings them together again.

To the lower end of a small vertical slide, *Q'*, below slide *Q*, and on the inner side of the frame *F*, a lever, *J*, pivoted at *j*, is attached, by means of a link, *O'*.

The opposite end of this lever is connected by a rod, *J'*, to a long hand-lever, *L*, which operates the whole apparatus.

The lever *L* is pivoted, at *l*, to the upper end of slide *Q*.

The movement of slide *Q* is limited by a slot, *r*, operating in connection with an adjustable pin, *r'*. The slide *Q'* is connected to the rock-bars *N N'* by means of crossed levers or arms.

When the handle of lever *L* is raised, the first effect is to raise the slide *Q*, the lever operating upon the pin *r* as a fulcrum, and thereby to throw back the two frames *A A'*, and the cutters with them. As soon, however, as the pin *r'* strikes the bottom of the slot *r*, it arrests the upward motion of the slide, and stops the frames *A A'*. The lever then operates upon the pin *l* as a fulcrum, and raises the lower slide *Q'*, thereby throwing back the pieces *E E'*, and retracting the cutter-blades independently of the frames.

When the lever *L* is depressed, it first throws down the slide *Q*, until the pin *r'* touches the top of the slot *r*, and then, changing its fulcrum, moves the slide *Q'* down, and advances the cutter-blades.

r v are adjustable stops, designed to limit the forward movement of the arms *n n'*, and of the parts *E E'*, and blades *e e*.

Having thus described my invention,

What I claim as new, and desire to secure by Letters Patent, is—

1. The movable frames *A A'* and cutter-shafts *B B'*, in combination with the movable parts *E E'* and cutter-blades *e e'*, when constructed to operate substantially as and for the purposes described.

2. The combination of rock-shafts *M M'*, crank *O O'*, slide *Q*, levers *L J J'*, rod *J'*, and adjustable stop *r*, when adapted to operate together, in the manner described, and for the purposes specified.

3. The arrangement of the cutters *e e*, heads *b b*, shafts *B B'*, *C C'*, *D*, and adjustable gearing *c c' c'' c'''*, *d d' d'' d'''*, when constructed and adapted to operate together, as and for the purposes set forth.

4. The arrangement of the cutter-shafts *B B'* with

the movable boxes *i i*, blocks *H H*, and screws *G G*, substantially as and for the purposes indicated.

5. The cutter-blades *e e*, of the form shown in fig. 4, when employed in connection with the heads *b b* and parts *E E'*, in the manner and for the purposes set forth.

6. The adjustable table *T'*, in combination with the

rocking-frame *T*, and screws *t t T'' T'''*, substantially as and for the purposes set forth.

To the above specification of my improvement, I have set my hand, this 27th day of January, 1869.
